(57) **CLAIM**

The ornamental design for a roof corral, as shown and described.

DESCRIPTION

FIG. 1 is an environmental perspective view of a roof corral, showing my new design;

FIG. 2 is a perspective view thereof;

FIG. 3 is a top view thereof;

FIG. 4 is a bottom view thereof;

FIG. 5 is a front view thereof;

FIG. 6 is a back view thereof;

FIG. 7 is a left side view thereof;

FIG. 8 is a right-side view thereof; and,

FIG. 9 is a frame member of the roof corral shown in isolation.

The broken lines of FIG. 1 illustrate environmental matter and form no part of the claimed design. The broken lines in FIGS. 2-9 depict portions of the roof corral that form no part of the claimed design.

1 Claim, 7 Drawing Sheets
